CLAIM

The ornamental design of a wheel assembly for poultry cage-top service vehicle, as shown and described.

DESCRIPTION

FIG. 1 is a top plan view of a wheel assembly for poultry cage-top service vehicle embodying my new design.

FIG. 2 is a front elevational view thereof.

FIG. 3 is a side elevation thereof.

FIG. 4 is another side elevational thereof viewed oppositely to FIG. 3.

FIG. 4

FIG. 1

FIG. 3

FIG. 2
